Application June 20, 1932, Serial No. 618,273

17 Claims. (Cl. 200—48)

This invention relates to disconnect switches in general, and more particularly to switches of the type including a relatively long blade that cooperates with a comparatively short contact.

5 In its more specific aspects the present invention is particularly concerned with the contact, its construction and manner of mounting. It is one of the objects of the present invention to provide a switch having an improved switch 10 contact that includes camming means for camming the contact and the blade apart as the blade moves toward its open position. The contact supporting structure is pivotally mounted so as to be drawn with the blade during the initial 15 switch opening operation, and is provided with a cam that rolls on the edge of the blade to cam the contact supporting structure from the blade. The contact supporting structure preferably comprises a housing that serves to protect the contact from rain, sleet, or snow, although it is within 20 the province of the present invention to make the contact supporting structure in the form of an open skeleton or frame.

It is a further object of the present invention 25 to provide a contact structure that may be standardized for use on various types of disconnect switches.

The attainment of the above and further objects of the present invention will be apparent 30 from the following specification taken in conjunction with the accompanying drawings forming a part thereof.

In the drawings:

Figure 1 is a top view of a switch embodying 35 the principles of my invention, said view showing the switch in its closed position;

Figure 2 is a view similar to Figure 1 showing the position of the parts during the opening of the switch;

40 Figure 3 is a side elevation of the switch shown in Figure 1;

Figure 4 is an enlarged side view of the housing shown in Figure 1;

45 Figure 5 shows a modified form of contact supporting structure;

Figure 6 is an end view of the structure of Figure 5;

50 Figure 7 is a side view of a rocking insulator type switch embodying the principles of my invention;

Figure 8 is a fragmentary view of an underhung type of switch employing my improved switch contact supporting structure;

55 Figure 9 is a side view of a portion of another

switch embodying the principles of my invention;

Figure 10 is a sectional view taken along the line 10—10 of Figure 9;

Figure 11 is a fragmentary view of another embodiment of my invention;

Figure 12 is a fragmentary sectional view taken along the line 12—12 of Figure 11; and

Figure 13 shows a modified form of switch blade.

Reference may now be had more particularly to the switch shown in Figures 1, 2 and 3. The switch comprises a grounded base 1 upon which is mounted a stationary insulator 2 and a rotatable insulator 3 in a manner well known in the art. A switch blade 4 is bolted or otherwise rigidly secured to the rotatable insulator and is swung thereby from its switch open position to its switch closed position. The stationary insulator 2 supports a contact structure that cooperates with the contact making end of the blade. A strain clamp and support 5 is bolted or otherwise rigidly secured to the insulator cap at the top of the insulator 2, being secured thereto in any preferred manner. The strain clamp 25 and support comprises a circular plate-like arm 6 that is secured to the insulator cap and from which there extends an upright portion 7 terminating in a short upper arm 8 extending forward thereof. A line clip supporting portion 10 is 30 integral with the upright portion 7 and extends rearwardly from about the center of the upright portion. The arm 10 is adapted to receive a line wire which is secured thereto by means of a U-shaped bolt 11 that passes through suitable slots 35 in the end of the arm 10 and secures the end of a line wire 13 in place. A suitable terminal 14 is secured to the line wire and is bolted to the arm 10, a flexible braided wire 12 being interposed between the terminal lug 14 and the arm 40 10.

The contact structure is pivotally mounted between the arms 6 and 3 and comprises a unitary cast metal housing 15 having a pair of rearwardly extending arms 16—16 that are pivoted between the arms 6—8 of the strain clamp and support 5. A pivot bolt or pin 17 extends through aligned holes in the arms 6—8 and through aligned holes in the arms 16—16 of the contact supporting structure 15. A torsion spring 19 biases the contact supporting structure 15 to its switch closed position.

The contact supporting housing 15 has a slit-like opening 20 at the front side thereof and an outwardly flared opening 21 at an adjacent trans-

10

verse side. During the switch closing operation the end of the switch blade enters the outwardly flared opening, being guided thereby, and then progresses into the slit-like opening 20. The opening 20 terminates in a finger 30 having a curved face 31, as indicated. A pair of contact shoes 23-23 are mounted within the housing, said contact shoes being pressed towards one another by coiled springs 24 and being guided towards and away from one another by a pair of bolts 25 that extend through oversized holes in the contact shoes. The springs 24 are held in position by studs 24' extending into the springs from the inner sides of the outer walls of the housing. The ends of the contact shoes are outwardly flared to guide the blade between them and are adapted to be spread apart as the blade enters between the contact shoes. For this purpose the contacting edge of the blade is wedge shaped to facilitate the spreading of the contact shoes. The contact shoes are connected to the line clip 17 by the flexible braided wire 12 that enters the housing 15 through an opening 26 in the front of the housing.

When the switch is open the contact housing 15 is in the position shown in Figure 1. As the end of the switch approaches its closed position, it first enters the outwardly flared opening 21 of the housing, and then it enters between the two contact shoes. As the blade continues moving in its closed position it finally reaches the position shown in the drawings.

To open the switch, the insulator 3 is rotated in a clockwise direction as seen in Figures 1 and 2. If there is a considerable pressure between the contact shoes and the blade, or if the blade is frozen to the contact assembly, the initial turning of the blade causes the housing to turn about its pivot 17, said housing being drawn by the blade. As the blade continues to move towards its open position the cam surface 31 bears against the edge of the blade 4 and rolls thereon to force the blade and contact shoes apart. When the blade leaves the housing the spring 19 returns the housing to the position shown in Figure 1, the stop 35 limiting the extent of clockwise turning of the housing.

It is to be noted that the blade 4 clears the contact finger 30 by a small amount when the switch is closed. This is of importance in the present invention and is obtained by providing a stop at a convenient place in the housing for preventing further movement of the blade in the housing during the closing operation, or it may be accomplished in any other desired manner, as by providing a limit stop for limiting the throw of the rotatable insulator 3 or of its actuating mechanism. As a result of the small spacing between the blade and the cam finger 30 there is a small switch opening movement of the blade before the cam 30 engages the blade. During this movement there is a certain amount of shearing action between the blade and the contact shoes tending to break the bond between them. Thereafter the cam finger 30 engages the blade and exerts a powerful force tending to pry the blade and the contact shoes apart.

In Figures 5 and 6 I have shown a side and end view of a skeletonized open frame that may be used in place of the closed hood structure 15. This structure is substantially similar to that shown at 15 in Figures 1, 2 and 3, differing therefrom essentially in that a portion of the top and bottom housing parts is omitted, as indicated by the opening 40. Instead of providing one side of the

structure shown in Figure 5 with a slit corresponding to the slit 20 that entire side of the contact supporting structure is open. Likewise, the outwardly flared guiding opening 21 of Figure 4 is omitted, the blade being in this instance guided between the contact shoes by the outwardly flared lips at the ends of the contact shoes, as indicated in Figure 4. It may therefore be seen that the skeletonized frame consists merely of two frame portions 41-41 joined at their rear by the connecting portion 42 and at their front by the cam portion 39 to form a unitary structure. In other respects this contact supporting structure is similar to that shown in the switch previously described, being provided with the pivoting ears 16 and with the cam 30 and with bolt receiving openings 25' for receiving the bolts on which the contact shoes slide, as in the previous case.

In Figure 7 I have shown my pivoted contact structure applied to an otherwise standard type of rocking insulator switch. This switch comprises a supporting base 45 on which is mounted a rocking insulator 46 that rocks about a center 47, being actuated by a crank 48 and a connecting rod 49. A stationary insulator 50 is mounted on the base 45 and constitutes a terminal for a line wire 51. A grasshopper linkage 52-53 connects the stationary insulator 50 with the rocking insulator 46 and supports a flexible conductor that extends the circuit from the line 51 to a contact 54 that is rigidly mounted at the end of the insulator 46 in a manner well known in the art. A stationary insulator 60 is mounted on the base 45 and has secured thereto a bifurcated contact support 61 between the arms of which is pivoted a contact supporting structure 15 which may be in all respects the same as the contact supporting structure disclosed in the switch shown in Figures 1, 2 and 3, or which may comprise a frame as shown in Figures 5 and 6. A web 62 is formed integrally with and extends between the two arms of the bifurcated support 61 at the outer ends thereof. This web not only serves to secure the outer ends together, but also acts to protect the contact housing pivot pin from sleet or snow. A stop 63 cooperates with the stop 35 on the contact housing to limit the extent of rotation of the housing about its pivot pin. A limit stop 64 limits the extent of rotation of the housing in the opposite direction. The housing 15 is biased counter-clockwise to its switch open position by gravity and by means of a torsion spring 19'. When the switch blade 54 is moved to its open or to its closed position by the corresponding rocking of the insulator 46, the contact housing 15 is moved therewith in the same manner as was previously set forth in connection with the switch shown in Figure 1.

Whether the spring 19' is to be arranged to bias the contact structure to its normal closed position or to a position at an angle thereto is determined by the question as to whether or not sleet hood protection is desired and as to which position of the hood affords a maximum protection against the entrance of sleet into the housing. Other things being equal it is desirable to arrange the spring to bias the contact structure to a position at an angle to its normal switch closed position so that when the switch is open it is maintained in the position to which it is moved by the blade during the opening operation. This serves a two-fold purpose. First, the spring 19' acts as a bumper spring to decelerate the blade during the switch closing operation, and, secondly, it assists the switch opening operation. Also, dur-

ing the closing operation there is a greater shearing or wiping action between the blade and the contacts, thereby producing a greater cleaning of the contacting surfaces. The switch shown in 5 Figure 3 is adapted to be mounted with the base 1 extending vertically and the insulator 2 above the insulator 3. It is therefore desirable to bias the contact structure to its normal switch closed position to afford a greater protection against the 10 entrance of sleet. Where such protection is of no great importance, or where the switch is mounted always in a position such that the sleet protection is not adversely affected, the spring 19 is arranged to bias the contact structure to the position 15 shown in Figure 2.

In Figure 3 I have shown my pivoted contact structure mounted on a switch of the underhung type. This is a type of switch wherein the supporting insulators are suspended from a mounting 20 base, the blade being actuated in any desired manner. The bottom of the contact supporting insulator is indicated at 70, said insulator having an insulator pin 71 secured thereto as in the usual practice. A contact support and line terminal anchor is indicated at 72. The contact support comprises a substantially flat circular plate-like portion 73 that is secured to the bottom of the insulator pin and has a pair of arms 74 extending therefrom. A line terminal clip 73' 30 that is adapted to receive a terminal at the end of a line wire is bolted or otherwise suitably secured to a web 74' that connects the lower ends of the pair of arms 74. A flexible braided conductor 75 is interposed between the clip 73' and the web 74', said braided conductor extending the circuit to the contact shoes within the housing 15.

The contact housing 15 extends between the bifurcated arms 74 and is pivoted thereto by means of a pivot pin 76 that extends through the arms 74 40 and the pivot arms of the housing 15. The contact housing may be biased to the open position by means of a torsion spring that surrounds the pin 76 in the same manner as the spring 19 of the switch shown in Figures 1 to 3 surrounds the pivot pin 76 of that switch. As the blade 4' swings downward to its switch open position the contact housing 15 is moved therewith in a manner such as was previously explained in connection with the switch shown in Figures 1-3. The spring, 45 and/or gravity, retain the housing in this position. A boss 77 is provided on the outside of one of the arms 74 for receiving an arcing horn if desired.

It is to be noted that the same contact housing 55 15 is used in each of the three types of switches herein shown. This permits of standardization in the manufacture of such contacts, thereby reducing the cost of manufacture and also reducing the amount of stock that must be carried on 60 hand.

In Figure 9 I have shown a fragmentary portion 65 of a switch of the type shown in my Patent No. 1,952,436, issued March 27, 1934, differing therefrom only in that the contact and contact supporting structure are different. In so far as the structure of this switch is the same as that of my aforesaid patent, above referred to, reference may be had to that patent for a more complete description of the details of various parts thereof 70 that do not constitute the subject matter of this application. Briefly stated, this switch comprises a stationary insulator 100 and an axially rotatable insulator 101 joined by a bracing frame 102. The frame is secured at one end to the stationary insulator and at its other end extends

between a pair of arms 103 and 104 of a yoke 105 that is secured to the rotatable insulator 101, being pivoted between said arms by a suitable pivot, thereby permitting a free rotation of the yoke through a limited angle. The yoke 105 has a 5 crank 106 formed therewith, which is connected, by means of a universal joint, to a connecting rod 107. At its other end the connecting rod is secured, through a universal joint 108, to a pull rod 109 and a guiding link 110. The guiding link 10 is pivoted about an axis 111 about which is also pivoted a blade 112. The blade and the link 110 are mechanically separate and independently movable about the axis 111. A cam 120 is pivoted to the opposite end of the blade through a pivot 15 pin 121, said cam having an arm 122 rigid therewith and pivoted at 123 to the opposite end of the pull rod 109. An arcing horn 124 is also carried by the pull rod. A contact making portion 125 is formed at the end of the blade, being, preferably, rigid with respect to the blade although it may be formed rigid with the cam 120 to pivot about the pivot pin 121, as shown in Figure 13. If desired, the contact making portion 125 may be pivoted about the pin 121 but mechanically independent of the cam, being biased to a given position in any preferred manner, as by means of a spring or the like.

The contact structure that cooperates with the contact making end of the blade comprises 30 a support 130 that is mounted upon a stationary insulator 131. The support includes an upwardly extending portion 132 against which the cam 120 is adapted to bear for forcing the contact making end of the blade upwardly. The contact support 35 also includes an upwardly extending portion 135 which acts as a support for a line wire terminal 136, a stationary arcing horn 137, and a pivot pin 139 about which is pivoted a skeletonized contact supporting frame such as is shown more 40 particularly in Figures 5 and 6. The contact shoes 23 are mounted upon the pins 25a that extend through oversized holes in the contact shoes to permit a limited degree of rocking as well as of sliding movement of the shoes on the pins, 45 as in the structures previously described. The pins 25a extend between the frame portions 41-41 of the skeletonized frame in a manner which is apparent from the description thus far given.

The contact structure of this switch departs 50 from the previously described constructions in that it employs a sleet hood over the skeletonized frame. The sleet hood comprises two similar hood members 145 and 146 which are mounted 55 upon the skeletonized frame by means of the frame pins 25a that support the contact shoes. For this purpose the pins are therefore appreciably longer than is required in the contact structures previously described. The sleet hood members are provided with openings 143 through which the pins 25a are passed, said openings being of a slightly larger diameter than the diameter of the pins and being provided with well rounded corners. As a result, the two sleet hood members 60 are permitted a limited amount of rocking movement with respect to the skeletonized frame. The sleet hood members are normally urged into engagement with one another by a pair of springs 149-149. Nuts 151 are provided 65 for holding the sleet hood members upon the pins and for adjusting the tension upon the spring members. The two sleet hood members abut against one another along the line 156-156, thus providing a protecting enclosure for the contact 70 75

shoes and for the portion of the blade contact 125 that may be in engagement with the contact shoes. The top of the sleet hood is downwardly and rearwardly inclined so as to provide suitable drainage for moisture. The rear of the sleet hood encloses the upper rear side of the contact structure, while the front portion of the sleet hood is provided with an opening 150 through which the blade contact 125 projects when the switch is closed. The two sleet hood members are provided with upwardly and outwardly flaring guiding members 160—161 for guiding the switch blade into position. As the blade moves downward between these guiding members during the switch closing operation it is accurately aligned with respect to the contact shoes and it forces the two sleet hood members apart. After the switch blade has entered the housing and projects through space 150, the two sleet hood members are again closed by the springs 169—169 thereby again enclosing the main contacts.

To open the switch the rotatable insulator 101 is rotated to turn the crank 103 and thereby exert a pull on the connecting rod 107 to pull 25 the rod 109 to the left as seen in Figure 9. This causes the cam 120 to turn about its pivot 121 and, since the cam bears against the stop 132 it exerts a powerful force tending to move the pivot pin 139 upwardly. This produces a powerful camming action that moves the blade upwardly. The frictional engagement of the contact shoes 23—23 causes the contact supporting structure, comprising the skeletonized frame, to swing about its pivot 139 and to bring the pry 30 loose finger 30 of the contact supporting structure into engagement with the lower edge of the blade portion 125. Thereafter, and in so far as concerns the action of the contact making portion of the blade 125 with respect to the contact shoes 23, the action is the same as in the cases of the switches previously described. It is to be remembered that the pivot pin 139 does not pass through the two sleet hood members 160—161 and therefore the sleet hood members move with 35 the contact supporting structure as that structure pivots about the pin 139. It is to be noted that the upper edge of the blade 125 is wedge-shaped. As the blade continues to move in its outward direction the wedge-shaped upper edge of the contact making portion of the blade engages the tapered portions 165—165 of the two sleet hood members and spreads them apart, said members rocking about the pins 25a. After 40 a predetermined amount of turning movement of the cam 120 about its pivot 121, a stop 122a on the arm 122 engages the blade and prevents further movement of the cam with respect to the blade. Thereafter continued rotation of the actuating insulator 101 causes the pull rod, the blade, and the guiding link 110 all to swing as 45 a truss member about the pivot axis 111 to the ultimate switch open position of the switch.

Reference may now be had more particularly to Figure 11 wherein there is shown a fragmentary portion of a modified form of contact arrangement incorporated in a switch of the type shown in Figure 9. In so far as the structure is the same as that shown in Figure 9 similar reference numerals have been used. The cam carried 50 by the blade is indicated at 120', its pivot at 121, the pivot between the pull rod 110 and the extension 122 of the cam lever at 123, and the stop for limiting the extent of turning of the cam about the pivot 121 at 122'. The stop 122' is an 55 integral part of the arm 122 and, upon limited

rotation thereof about the pivot 121, it abuts against the blade. The contact supporting structure is indicated in general by the reference numeral 200, being pivoted at 17a and carrying the contact shoes 202 in the same manner as was previously described. The camming finger is indicated at 203. It is to be noted that when the switch blade is in its closed position the end of the blade slightly clears the camming finger 203, a stop 205 being provided on the contact structure for this purpose. It is to be noted that in this construction the pivot 17a for the contact supporting structure is located between the blade pivot and the point of engagement of the blade with the contact shoes, rather than on the opposite side 10 of the point of engagement of the two. By this arrangement a more powerful action is obtained than what is obtained in the switch shown in Figure 1, or the switch as shown in Figure 9, in that there is a smaller relative movement between 15 the contact supporting structure and the blade for a given angular movement of the blade, and therefore there is a greater mechanical advantage.

The switch shown in Figure 11 may be provided 20 with a hood similar to that provided for the switch shown in Figure 9. At 143' I have shown one of the two hood portions provided for this switch. The other hood portion has been removed in order to show the contact arrangement within 25 the hood. It is to be noted that the hood is provided with a rear wall 235, as well as with the sloping top wall. The hood portions for this switch are mounted upon the pins 25a—25a in the same manner as was previously described in 30 connection with the switch of Figure 9. Most of the moisture that may fall upon the top of the housing comprising the two hood members will drain therefrom due to the slope thereof. However, a small amount of moisture may creep along 35 the abutting surfaces of the two sleet hood members and thus get into the housing. If this is objectionable the two hood members may be provided with a suitable trapping portion for trapping this moisture and draining it away. The 40 trap or drain is indicated at 210 and consists merely of a trough immediately below the top of the abutting edges of the two sleet hood members. The side edge of the bottom of the trough 210 is sloped upwardly, as may be seen at 211 in Figure 12. As a result of this arrangement it is 45 apparent that any moisture that may enter the trough 210 will be guided away from the outer edge thereof and will flow in the trough along the top of the housing and down the rear side 50 205 thereof. The bottom of this trough is located at the rear of the housing and is open so that the moisture may flow outward freely. The sleet hood members of the switch shown in Figure 9 may be provided with a trough similar to the 55 trough 210. In the case of the sleet hood shown in Figure 9, the lower rear portion must be provided with an opening to permit the contact supporting structure to extend rearwardly therethrough to its pivot, and therefore the drain trough at the rear wall thereof terminates in an open end substantially above the bottom of the housing. In other respects the housing shown in Figure 9 is the same as that shown in Figure 11.

In Figure 13 I have illustrated an arrangement 70 wherein the contact making portion of the blade is rigid with the camming member, rather than with the blade itself. The blade is indicated at 112 and has a forked member 112a secured thereto. The contacting making end of the blade is 75

indicated at 125a, being an integral part of the cam portion 120a, and being pivoted between the arms 112a of the forked member by the pin 121. A flexible braided copper wire 220 extends the circuit from the switch blade 112 to the contact making portion 125a thereof, thereby bypassing the pivot 121 in so far as concerns the current carrying function of the blade. The type of blade shown in Figure 13 may be embodied 10 in the switch shown in Figure 9 or in the switch shown in Figure 11, if desired.

In compliance with the requirements of the patent statutes I have herein shown and described a few preferred embodiments of my invention. It is, however, to be understood that the invention is not limited to the precise constructions herein shown, the same being merely illustrative of the principles of my invention.

What I consider new and desire to secure by Letters Patent is:

1. A pivotally mounted contact housing comprising a substantially box-like structure having a slit opening on one side merging at one end with an outwardly flared opening at an adjacent side for receiving a switch blade, a stop member extending outwardly of the housing adjacent the opposite end of the slit and having a curved camming surface, a pair of mounting ears projecting from the housing from adjacent the side opposite the side having the slit opening, a pivotal mounting for the housing including a pivot pin extending through the mounting ears, spring means biasing the housing about its pivot to a predetermined normal position, stop means for limiting the extent of turning of the housing about its pivot to a fractional part of a half revolution, and contact means mounted within the housing and adapted to receive a blade.

2. A contact housing comprising a substantially box-like structure having an opening at one side for receiving connecting leads and having a blade receiving slit opening on the same side merging at one end with an outwardly flared opening at an adjacent side, said first mentioned opening and said blade receiving slit opening being separated by a member formed integrally with the housing and extending outwardly thereof and having a curved camming surface facing the blade receiving opening, and contact means mounted within the housing.

3. A contact supporting structure comprising a unitary frame having integral parallel spaced rearwardly extending ears adapted to receive a pivot pin for pivotally mounting the structure, a pair of contact shoes carried by the contact structure and spring pressed towards one another, said contact shoes being outwardly flared at their outer end for guiding a blade between them, said structure being adapted to be drawn about its pivot by the outward swinging of a blade from between the contact shoes, abutment means comprising an integral part of the supporting structure, said abutment means comprising a curved camming surface extending outwardly of said frame along said blade and normally spaced therefrom, said means being adapted to bear against the switch blade only after initial opening movement and pry the supporting structure and the switch blade apart as the switch blade is moved outward of the contact shoes, means for limiting the extent of pivotal motion of the supporting structure in one direction, and means for limiting the extent of pivotal motion of the supporting structure in the opposite direction.

4. A switch comprising a switch blade and a pivoted contact structure engageable thereby, said contact structure including contact making means having frictional engagement with the blade whereby, upon movement of the blade outward of the contact making means, the contact structure is turned about its pivot, cam means on the contact structure initially moved into camming engagement with the blade as the blade moves outward of the contact making means, and means for returning the contact structure to its switch closed position after the blade moves out of engagement therewith.

5. In a switch, the combination of a relatively short contact member, a relatively long switch arm swingable into and out of engagement therewith, pivots for said contact member and said switch arm providing for large angular movement of said arm upon a relatively small angular movement of said switch arm, said contact member being freely swingable and swung toward the open position by the opening movement of said arm, cam means movable with the contact member for forcing the contact member and the switch arm out of engagement during switch opening operation, and spring means for biasing the contact member to the switch closed position.

6. A contact supporting structure comprising a frame having means for pivotally mounting the same, contact means carried by the structure and adapted to receive a blade, stop means for limiting the extent of engagement of the contact means by a blade, said structure being adapted to be drawn about its pivot as a blade is moved therefrom, and pry loose cam means comprising an integral part of the structure and out of engagement with a blade that is in engagement with the contact, said cam being brought into camming engagement with the blade as the contact structure is drawn about its pivot by the switch opening movement of the blade, to pry the contact structure and blade apart.

7. A contact supporting structure comprising a frame having means for pivotally mounting the same about a stationary pivot, contact means carried by the structure and adapted to receive cooperating contact making means, stop means for limiting the extent of engagement of the contact means with the contact making means, said structure being adapted to be swung about its pivot by the frictional engagement between the two contacting means upon the initiation of the separating movement of the two contacting means, cam means carried by said structure and movable into independent engagement with the contact making means after a predetermined separating motion of the two contacting means for prying the two contacting means apart, and spring means for biasing the contact means about its pivot to a predetermined position.

8. A contact supporting structure comprising a frame having means for pivotally mounting the same about a stationary pivot, contact means carried by the structure and adapted to receive cooperating contact making means, stop means for limiting the extent of engagement of the contact means with the contact making means, said structure being adapted to be swung about its pivot by the frictional engagement between the two contacting means upon the initiation of the separating movement of the two contacting means, cam means carried by said structure and movable into independent engagement with the

contact making means after a predetermined separating motion of the two contacting means for prying the two contacting means apart, and a sleet hood carried by said contact supporting structure and having a rocking motion with respect thereto.

9. A switch comprising a contact structure mounted for swinging movement, a switch blade swingable into and out of engagement therewith, cam means carried by the switch blade for initiating the switch opening movement of the blade, said structure being swung by the blade upon the initial switch opening movement of the blade, and cam means carried by the contact structure and engaging the blade to pry the contact structure and blade apart.

10. A switch comprising a stationary insulator, a contact pivotally mounted thereon, a switch blade swingable into and out of engagement with the contact, a pull rod extending substantially the full length of the blade, a cam member pivoted on the blade and having pivotal connection with the pull rod whereby the pull rod actuates the cam member to impart an initial powerful switch opening movement to the blade, abutment means between the cam and the blade whereby upon continued movement of the pull rod the blade is moved therewith as a unit, said contact being drawn about its pivot by the frictional engagement with the blade, and cam means carried by the contact and independently engaging said blade after predetermined rotation of said contact about its pivot for prying the contact and the blade apart.

11. A switch having a relatively short pivoted contact member and a relatively long pivoted switch arm movable into and out of engagement therewith, the point of engagement of the contact and the arm being adjacent the contact pivot and remote from the arm pivot, characterized in that the contact pivot is located between the blade pivot and the point of engagement of the blade with the contact, whereby the direction of rotation of the contact is the same as that of the blade during the initial switch opening movement, and cam means carried by the contact for forcing the blade out of the contact after a predetermined rotative movement thereof, said cam means engaging said blade only during switch opening movement thereof.

12. A switch including a relatively short pivoted contact member and a relatively long pivoted switch arm movable into and out of engagement therewith, a relatively short prying cam pivoted on the switch arm adjacent the contact making end thereof, a pull rod pivoted to the cam for swinging it about its pivot on the switch arm in one direction to initiate the switch opening movement, said contact member being drawn about its pivot in an opposite direction by the switch arm, a second cam carried by said contact member for forcing it from the switch arm during the switch opening movement, abutment means between the prying cam and the switch arm for limiting the relative movement between the two and swinging the switch arm about its own pivot to its full open position upon continued pull of the pull rod, and a guiding link pivoted adjacent the pivoted end of the blade and connected to the pull rod for guiding the end of the pull rod independently of the switch arm.

13. A switch of the class described including a contact structure comprising a unitary frame having an outwardly flared opening at one side thereof, a slit along an adjacent side communicat-

ing with said opening, a pair of integral projecting pivot lugs extending from said frame on the side opposite said slit, and spring-pressed contact members carried within said frame and flared outwardly toward said flared opening, said frame having integral guide means upon which said contact members are mounted.

14. A switch of the class described including a contact structure comprising a unitary frame having an outwardly flared opening at one end thereof, a slit along an adjacent side communicating with said flared opening, a pair of integral projecting pivot lugs extending from said frame on the side opposite said slit, spring-pressed contact members carried within said frame and flared outwardly toward said opening, said frame having integral guide means upon which said contact members are mounted, and a cam member projecting outwardly of said frame from the side having the slit formed therein and having a camming surface curved outwardly away from said slit.

15. A switch of the class described including a contact structure comprising a unitary frame having an outwardly flared opening at one side thereof, a slit along an adjacent side communicating with said flared opening, a pair of integral projecting pivot lugs extending from said frame on the side opposite said slit, spring-pressed contact members carried within said frame and flared outwardly toward said opening, said frame having integral guide means upon which said contact members are mounted, and means extending through said frame for securing said contact members in position therein, and a pair of opposed sleet hood members enclosing said frame and having spring-pressed rocking movement about said securing means.

16. A switch comprising a pair of insulator stacks, one of said stacks being rotatable, a switch blade carried by said rotatable stack, a contact cap mounted on the other of said stacks, a pivot pin carried by said cap, a contact supporting frame having integral spaced ears supporting said frame for rotation about said pivot, spring-pressed contact members carried within said frame, means on said pivot for biasing said frame into a predetermined position, stop means on said frame for limiting movement of said blade between said contact members, a curved camming member formed integral with said frame and disposed out of engagement with said blade in switch closed position, rotation of said blade in switch opening direction initially swinging said frame about said pivot in the opposite direction, said camming member subsequently engaging said blade to pry the same out of engagement between the contact members.

17. In combination, a pair of insulator stacks, one of said stacks being rotatable, a switch blade carried by said rotatable stack and movable into switch closing position over the other stack, a contact supporting frame pivoted on said other stack, contact means within said frame adapted to be engaged by said blade, stop means for limiting switch closing position of said blade, and cam means carried by said contact frame and normally disposed out of contact with said blade, said cam means independently engaging said blade only during switch opening movement thereof for prying said blade out of engagement between said contact members.
